UNITED STATES PATENT OFFICE.

EDWIN E. SLICK, OF PITTSBURGH, PENNSYLVANIA.

DESIGN FOR A GOBLET OR SIMILAR ARTICLE.

Application filed August 22, 1928. Serial No. 27,908. Term of patent 14 years.

To all whom it may concern:

Be it known that I, EDWIN E. SLICK, a citizen of the United States, residing at Pittsburgh, in the county of Allegheny and State of Pennsylvania, have invented a new, original, and ornamental Design for Goblets or Similar Articles, of which the following is a specification, reference being had to the accompanying drawing, forming a part thereof and in which the figure is a perspective view of a goblet, showing my new design.

The dominant feature of the design is the provision of droplets, which are intended to simulate droplets of liquid on the sides of the goblet.

I claim:

The ornamental design for a goblet or similar article, substantially as shown and described.

In witness whereof, I have hereunto set my hand.

EDWIN E. SLICK.
